UNITED STATES PATENT OFFICE

ARTHUR BATES, OF LEICESTER, ENGLAND, ASSIGNOR TO UNITED SHOE MACHINERY CORPORATION, OF PATERSON, NEW JERSEY, A CORPORATION OF NEW JERSEY

MACHINE FOR SHAPING SHOE UPPERS

Original application filed January 11, 1930, Serial No. 420,251, and in Great Britain January 22, 1929.
Divided and this application filed June 8, 1931. Serial No. 542,853.

This invention relates to machines for use in the manufacture of shoes, and more particularly to machines for shaping shoe upper materials over lasts or other forms, this application being a division of my copending application Serial No. 420,251, filed on January 11, 1930. The invention is herein illustrated in its application to a machine designed for use in the manufacture of shoes of the welt type, but it is to be understood that in various novel and useful aspects it is not thus limited in its applicability.

While it is the more common practice in the manufacture of various kinds of shoes, including welt shoes, to perform the side-lasting operation prior to the shaping or lasting of the toe and heel ends of the upper materials, there have nevertheless been proposed and utilized heretofore to some extent methods involving the shaping of at least the toe-end portion of the upper materials (hereinafter referred to inclusively as the upper) to the contour required for the finished shoe prior to the lasting of the sides at the rear of the toe end. Such is the practice, for example, where the toe-end portion of the upper is molded substantially to its final shape before the upper is mounted on a last. Likewise, in that process of shoe manufacture which involves the sewing of a welt to the shoe simultaneously with the lasting of its opposite sides, as disclosed in my earlier application Serial No. 325,839, filed on December 13, 1928, the final shaping or lasting of the toe-end portion of the upper is preferably effected prior to the lasting of the sides at the rear of the toe.

It is an object of the present invention, in one important aspect, to provide a machine for shaping the toe-end portions of uppers under such conditions as to facilitate the later side-lasting operation and also to minimize any tendency for a previously shaped toe to be disturbed by the side-lasting operation or for that operation to be restricted in its effectiveness by reason of the previous shaping of the toe. For the purpose in view, the machine herein shown accordingly comprises a novel organization of means for shaping the toe-end portion of the upper and for

positioning and holding the forepart of the upper at the rear of the toe in close conformity to the contour of the form or last over which the upper is shaped during the shaping of the margin of its toe-end portion as required for its permanent attachment to an insole. More particularly, as illustrated, there is provided, in combination with means for applying a pull to the toe end of the upper to tension it over the last and for thereafter wiping the margin of its toe-end portion into lasted relation to an insole on the last, a fluid-pressure device arranged to embrace the forepart of the upper at the rear of the toe and to press it into close conformity to the contour of the last after the upper-tensioning operation has been substantially completed and to hold it thus conformed to the last during the wiping of the margin of its toe-end portion over the insole. The fluid-pressure device herein shown comprises an inflatable pad so constructed and arranged as to apply pressure to the upper over a continuous area including the hollow back of the toe and the top of the instep and also the opposite sides as far rearwardly as the ball of the shoe. As a result of such close conformity of the forepart of the upper at the rear of the toe to the contour of the form or last at the time when the marginal portion of the upper around the toe is shaped as required for its permanent attachment to an insole, the marginal toe portion and the portion of the upper immediately at the rear of the toe are positioned substantially in the relation to each other required for the finished shoe and tend to maintain that relation thereafter, even though the margin of the forepart of the upper at the rear of the toe is left unfastened, as illustrated, until the side-lasting operation is performed. There is accordingly no undue tendency in the side-lasting operation to disturb the previously shaped margin of the toe-end portion of the upper, nor is the effectiveness of the side-lasting operation in locations adjacent to the toe portion of the upper unduly restricted by reason of the previous shaping of the toe portion.

While the machine herein shown, as above

described, comprises fluid-pressure means for conforming an upper at the rear of the toe to the contour of a form or last, in combination with other means for shaping the toe-end portion of the upper, it will be recognized that in some of its novel aspects the invention is not limited to such a combination nor to an organization having fluid-pressure conforming means arranged to operate upon that particular portion of the upper.

10 The novel features of the invention, including various novel details of construction and combinations of parts, will now be more particularly described by reference to the accompanying drawings and thereafter pointed out 15 in the claims.

In the drawings,

Fig. 1 is a view partly in side elevation and partly in section, showing portions of 20 a toe-lasting machine in which novel features of the invention are embodied, this figure illustrating the tensioning of the upper over the last prior to the application of any substantial pressure to the forepart of the upper at the rear of the toe;

25 Fig. 2 is a view similar to Fig. 1, illustrating the pressing of the upper at the rear of the toe in close conformity to the contour of the last and the shaping of the margin of 30 the upper about the toe in lasted relation to the insole;

Fig. 3 is a plan view of the means shown in Figs. 1 and 2 for pressing the upper at the rear of the toe closely about the last;

35 Fig. 4 is a view of a portion of the mechanism shown in Fig. 3 as it appears when viewed in the direction of the arrow shown in Fig. 1; and

40 Fig. 5 is a perspective view of the toe portion of the shoe as it appears after it has been operated upon by the machine shown in Figs. 1 and 2.

The machine illustrated in Figs. 1 and 2 for lasting the toe end of the shoe is a machine of the same general character as that disclosed in Letters Patent No. 1,702,397 granted on February 19, 1929, upon an application of W. C. Baxter, and accordingly only such parts of the machine as it is necessary to refer to for an understanding of this invention are shown and will be described in detail. The machine is adapted to operate upon the toe portion of an upper loosely mounted on a last which is supported at its heel end on a spindle 10 and is further controlled by means of a heel rest 12, the spindle and heel rest being movable with the last in directions heightwise and lengthwise of the last, as more fully disclosed in the Letters Patent mentioned. For wiping the margin of the toe end portion of the upper inwardly into lasted relation to an insole *a* on the last, there are provided toe-embracing wipers 14, only one of which is seen in the drawings, and co-operating with these wipers are

clamp members 16 which clamp the margin of the upper upon the top face of the wipers for the purpose of applying a pull to the toe end of the upper to tension the upper over the last. The machine herein shown is also provided with grippers 17, only one of which is seen in the drawings, for gripping the upper at the opposite ends of the tip line in the manner disclosed in Letters Patent No.

1,706,474, granted on March 26, 1929, upon an application of W. C. Baxter. It will be understood that initially the last is presented at a higher elevation and farther forwardly than illustrated in Fig. 1 and that after the clamping of the margin of the upper upon the wipers and by the grippers the last receives a rearward movement to subject the upper to a lengthwise pull in the manner fully disclosed in Letters Patent No. 1,702,

397. Thereafter the toe end of the insole *a* is engaged by a clamping plate 18 supported on a downwardly swinging arm 20 and its shank portion by a presser foot 21 also mounted on this arm, and by this means the last is depressed relatively to the wipers, clamp members and grippers for further tensioning the upper over the last. Fig. 1 illustrates the positions of the parts at the end of this downward movement of the last, the toe end of the shoe at this time being pressed downwardly upon a toe rest 22 which in the construction herein shown is mounted in a fixed position upon a toe rest support 24.

For pressing the forepart of the upper in close conformity to the contour of the last at the rear of the toe, the machine herein shown is provided with a fluid-pressure device comprising an inflatable rubber pad 26 supported upon a casing 28 which is mounted on the toe rest support 24 in a manner hereinafter described. The casing 28 and the pad 26 are of such form and dimensions as to embrace the upper and last at the rear of the toe and to extend rearwardly over the high part of the instep and along the sides of the last as far as the ball of the shoe. The casing 28 is pivotally supported at its front end on a pin 30 mounted in a block 32 (Fig.

4) which is mounted to turn about a pin 34 at right angles to the pin 30, so that a substantially universal joint is provided between the casing and its support 24. The casing 28 is permitted to rock laterally about the pin 30 to adjust itself to the swing of different lasts, and for controlling such movement there are provided leaf springs 36 arranged to bear respectively on the opposite side portions of the casing to centralize it when there is no last in the machine. For determining the position of the casing 28 in respect to movement about the pin 34, there is provided a member 38 having a ball-shaped end positioned in a socket formed in the casing, the member 38 being adjustable to vary the po-

85 90 95 100 105 110 115 120 125 130

sition of the casing, as may be required for shoes of different shapes or sizes.

For expanding or inflating the pad 26 to apply pressure to the upper, it is contemplated that there will be provided a suitable pump and reservoir for compressed air (not herein shown), although it is to be understood that the utility of the upper-pressing means does not depend upon the use of fluid of that particular character. Leading from the compressed air supply to a valve 40 is a pipe 42, and leading from the valve to the pad 26 is a flexible pipe 44. The valve 40 herein shown is a hand-operated valve controlled by a hand lever 46 (Fig. 3). It will be understood that when the valve 40 is in the position illustrated in Fig. 2 the pipes 42 and 44 are in communication with each other through a peripheral recess in the valve, and that when the valve is in the position shown in Fig. 1 this communication is interrupted and the pipe 44 is connected to the atmosphere through an opening 48 in the valve.

It will be understood that in the downward movement of the last hereinbefore described it is carried into the recess provided by the casing 28 and the pad 26, but no substantial pressure is applied to the upper by the pad until after the parts have arrived in the positions illustrated in Fig. 1, as will be evident by reference to the cross-sectioned portion of the pad and adjacent shoe and last parts in that figure. With the parts of the machine thus positioned and the machine preferably at rest, the operator manipulates the valve 40 to admit compressed air to the pad, whereupon the pad is expanded and presses the upper in close conformity to the contour of the last. It will be observed that such pressure is applied over a continuous area including the hollow back of the toe and the top of the instep and extending also over the sides of the last nearly as far as the edge of the last bottom and as far rearwardly as the location of the ball of the shoe. The pressure is accordingly applied by the pad to substantially all portions of the forepart of the upper at the rear of the toe. After the pressure has thus been applied, the machine is again started and the wipers 14 are operated to wipe the margin of the upper inwardly over the insole around the end and along the sides of the toe to its final lasted position, as illustrated in Fig. 2, the clamp members 16 preferably continuing to press the margin of the upper upon the wipers during a portion, at least, of this operation to render them more effective to pull the upper tightly over the last and insole. Near the end of the wiping operation the clamp members are lifted and the grippers 17 also opened. During this operation the forepart of the upper at the rear of the toe is maintained in close conformity to the contour of the last by the pressure pad, which in addition to its conforming

action serves to hold the upper in that location against loss of such tension as it received from the pull of the clamping and gripping means thereon, while also assisting in supporting the last.

The parts shown in Figs. 1 and 2 include a trimming knife 50 movable to trim the margin of the upper flush with the upper face of the wipers 14 in the same manner as disclosed in Letters Patent No. 1,702,397. It will be understood that after removing the shoe from the machine the operator will detach the opposite ends of the strip of waste material from the remainder of the upper, so that the toe portion of the shoe will appear as indicated in Fig. 5. Preferably the machine will come to a stop at the end of the upper-trimming operation to allow time for the margin of the toe-end portion of the upper, including the toe stiffener, to set in its lasted shape, and the operator may then, if desired, insert a fine wire staple *s* to fasten the upper to the lip of the insole at each end of the tip line. As illustrated, the forepart of the upper at the rear of the toe is left in an unfastened condition. The pause in the operation of the machine at this point will also enable the operator to release the air pressure from the pad 26, so that when the arm 20 is raised the pad will not be unduly expanded.

If, as preferred and as above described, no portion of the upper has been shaped to conform to the contour of the last prior to the lasting of the toe, the heel-end portion of the shoe may next be lasted in any suitable manner after removal of the shoe from the illustrated machine, and the side-lasting operation thereafter performed either with or without simultaneous attachment of a welt to the shoe in the manner disclosed in application Serial No. 325,839.

From the foregoing description it will be evident that by use of the illustrated machine the toe-end portion of the upper is shaped over the last and the insole under such conditions as to treatment of portions of the upper at the rear of the toe as to facilitate the later side-lasting operation and to insure that the effectiveness of that operation will not be unduly restricted by the previously shaped or lasted toe and also to insure against any undue tendency for the side-lasting operation to disturb on the last the position of the previously shaped toe. That is to say, with the toe-end portion of the upper shaped under the conditions described, the forepart of the upper at the rear of the toe is thereafter positioned in such relation to the last and to the previously shaped toe that there is but little looseness to be taken up in the side-lasting of that portion of the upper and therefore no need in that operation of subjecting the upper to any-

thing more than very localized and restricted tensions.

While the invention is herein illustrated in its application to a machine particularly designed for shaping an upper over a last and over an insole on the last, it is to be understood that, in various novel aspects, it is not limited to a machine for shaping the upper over a form of that particular character or over an insole, and also that in some novel aspects the invention is not limited to a machine for shaping the toe-end portion of the upper prior to the side lasting of the shoe.

15 The novel method of making shoes herein disclosed is not claimed herein, but in the copending application of which this application is a division.

Having described the invention, what I claim as new and desire to secure by Letters 20 Patent of the United States is:

1. In a machine for shaping the toe-end portions of uppers, the combination with means for applying a pull to the toe end of an upper to tension the upper over a form and for thereafter shaping the margin of the toe end of the upper over the form, of fluid-pressure means conformable to the contour of the form and arranged to be rendered operative only after the upper-tensioning 25 operation has been substantially completed to press the forepart of the upper at the rear of the toe closely about the form and to hold it pressed against the form during the shaping of the margin of the toe end of the upper.

2. In a machine for shaping the toe-end portions of uppers, the combination with means for applying a pull to the toe end of an upper to tension the upper over a form and for thereafter shaping the margin of the toe end of the upper over the form, of fluid-pressure means conformable to the contour of the form and arranged to be rendered operative only after the upper-tensioning 40 operation has been substantially completed to press the forepart of the upper over the top and the sides of the form closely about the form and to hold it under pressure during the shaping of the margin of the toe end of the upper.

3. In a machine for shaping the toe-end portions of uppers, the combination with means for applying a pull to the toe end of an upper to tension the upper over a form and for thereafter shaping the margin of the toe end of the upper over the form, of a pad expandible by fluid pressure and arranged to be rendered operative only after the upper-tensioning operation has been substantially completed to press the forepart of the upper at the rear of the toe closely about the form and to hold it pressed against the form during the shaping of the margin of the toe end of the upper.

65 4. In a machine for shaping the toe-end

portions of uppers, the combination with means for clamping the margin of an upper around the toe and for tensioning the upper over a form by a pull on said clamped margin, said clamping and tensioning means including wipers for thereafter wiping the margin of the upper inwardly over the bottom of the form, of fluid-pressure means conformable to the contour of the form and arranged to be rendered operative after the upper-tensioning operation has been substantially completed to press the forepart of the upper at the rear of the toe closely about the form and to hold it pressed against the form during the wiping of the margin of the toe end of the upper inwardly over the form.

5. In a machine for shaping the toe-end portions of uppers, the combination with means for clamping the margin of the toe end of an upper, including members movable to shape the margin of the upper over a form, and means for moving the form relatively to said clamping means to tension the upper prior to the shaping of its margin, of fluid-pressure means arranged to be rendered operative after the upper-tensioning operation has been substantially completed to press the forepart of the upper at the rear of the toe in close conformity to the top and sides of the form and to hold it during the shaping of the margin of the toe end of the upper over the form.

6. In a machine for shaping the toe-end portions of uppers, the combination with wipers for wiping the margin of the toe end of an upper inwardly over a form, and means for pressing the margin of the upper upon said wipers to render them effective to pull the upper tightly over the form in the wiping operation, of means expandible by fluid pressure for pressing the forepart of the upper in close conformity to the top and sides of the form during the wiping action of the wipers.

7. In a machine for shaping the toe-end portions of uppers, the combination with wipers for wiping the margin of the toe end of an upper inwardly over a form, and means for pressing the margin of the upper upon said wipers to render them effective to pull the upper tightly over the form in the wiping operation, of means expandible by fluid pressure for pressing the forepart of the upper in close conformity to the top and sides of the form during the wiping action of the wipers, said pressing means being limited substantially to engagement with the upper at the rear of its toe portion.

8. In a machine for shaping shoe uppers, the combination with means for applying a pull to an upper to tension it over a form, of fluid-pressure means arranged to be rendered operative only after the upper-tensioning operation has been substantially completed to press the upper in close conformity to the contour of the form.

9. In a machine for shaping shoe uppers, the combination with means for applying a pull to the forepart of an upper to tension it over a form, of a toe rest for engaging the toe end of the upper, and a pad arranged to engage the forepart of the upper at the rear of said toe rest and expansible by fluid pressure after the upper-tensioning operation has been substantially completed to press the upper in close conformity to the contour of the form. 70
10. In a machine for shaping shoe uppers, the combination with means for clamping the margin of the forepart of an upper, and means for moving a form relatively to said clamping means to tension the upper over the form, of a pad toward which the form is thus movable, said pad being expansible by fluid pressure to hold the upper in close conformity to the contour of the form after the upper-tensioning operation. 75
11. In a machine for shaping shoe uppers, the combination with means for applying a pull to an upper to tension it over a form and for thereafter shaping its marginal portion over the form, of fluid-pressure means arranged to be rendered operative only after the upper-tensioning operation has been substantially completed to press the upper closely about the form and to hold it during the shaping of its marginal portion. 80
12. In a machine for shaping shoe uppers, the combination with means for shaping the toe-end portion of an upper over a form, of fluid-pressure means for pressing the forepart of the upper in conformity to the top and sides of the form, said fluid-pressure means being arranged to engage the sides of the upper only at the rear of its toe portion. 85
13. In a machine for shaping shoe uppers, the combination with means for shaping the toe-end portion of an upper over a form, of a pad arranged to embrace the forepart of the upper at the rear of the toe and expansible by fluid pressure to press the upper in close conformity to the contour of the form, said pad being limited substantially to engagement with the upper at the rear of its toe portion. 90
14. In a machine for shaping the toe-end portions of uppers over lasts, the combination with means for applying a pull to the toe end of an upper to tension it over a last and for thereafter shaping the margin of the toe end of the upper in lasted relation to an insole on the last, of fluid-pressure means conformable to the contour of the last and arranged to be rendered operative only after the upper-tensioning operation has been substantially completed to press the forepart of the upper at the rear of the toe in close conformity to the top and sides of the last and to hold it pressed against the last during the shaping of the margin of the toe end of the upper over the insole. 95
15. In a machine for shaping the toe-end portions of uppers over lasts, the combination with means for applying a pull to the toe end of an upper to tension it over a last and for thereafter shaping the margin of the toe end of the upper in lasted relation to an insole on the last, of a pad expansible by fluid pressure and arranged to be rendered operative only after the upper-tensioning operation has been substantially completed to press the forepart of the upper at the rear of the toe in close conformity to the top and sides of the last and to hold it pressed against the last during the shaping of the margin of the toe end of the upper over the insole. 100
16. In a machine for shaping the toe-end portions of uppers over lasts, the combination with means for applying a pull to the toe end of an upper to tension it over a last and for thereafter shaping the margin of the toe end of the upper over the bottom of the last, of means arranged to be rendered operative only after the upper-tensioning operation has been substantially completed to press the forepart of the upper at the rear of the toe in close conformity to the contour of the last over a substantially continuous area extending over the top of the last and along the sides thereof as far rearwardly as the ball of the shoe. 105
17. In a machine for shaping the toe-end portions of uppers over lasts, the combination with means for applying a pull to the toe end of an upper to tension it over a last and for thereafter shaping the margin of the toe end of the upper over the bottom of the last, of fluid-pressure means arranged to embrace the forepart of the upper at the rear of the toe and to extend rearwardly along the instep and also along the sides of the last as far as the ball of the shoe for pressing the upper closely about the last only after the upper-tensioning operation has been substantially completed and for holding it during the shaping of the margin of its toe end portion. 110
18. In a machine for lasting the toe ends of uppers, the combination with means for applying lasting tension to the margin of the toe end of an upper and for thereafter wiping the margin of the toe end portion of the upper into lasted relation to an insole on the last, of an inflatable pad arranged to be rendered operative only after the upper-tensioning operation has been substantially completed to press substantially the entire forepart of the upper at the rear of the toe in close conformity to the last and to hold it thus conformed to the last during the wiping of its margin into lasted relation to the insole. 115
19. In a machine for lasting the toe ends of uppers, the combination with toe-lasting means for tensioning an upper over a last and for thereafter shaping its margin in lasted relation to an insole on the last, and means for moving the last relatively to said lasting. 120

means to tension the upper, of fluid-pressure means arranged to engage the forepart of the upper at the rear of the toe and to be rendered operative after the tensioning of the upper has been substantially completed to press the upper in close conformity to the contour of the last and to hold it during the shaping of the margin of its toe end portion over the insole.

20. In a machine for lasting the toe ends of uppers, the combination with wipers and clamping means arranged to clamp the margin of the toe end of an upper between them, and means for moving a last relatively to said wipers and clamping means to tension the upper over the last, said wipers being movable thereafter to wipe the margin of the toe end of the upper into lasted relation to an insole on the last, of a pad arranged to embrace the forepart of the upper at the rear of the toe over the top and the sides of the last and expandible by fluid pressure to press the upper in close conformity to the contour of the last after the upper-tensioning operation and to hold it during the wiping of its margin inwardly over the insole.

21. In a machine for shaping uppers over lasts, the combination with means for clamping the margin of the forepart of an upper, of means for engaging an insole on a last at the toe end and in the shank to move the last relatively to said clamping means to tension the upper, and a fluid-pressure device toward which the last is thus movable arranged to embrace the forepart of the upper at the rear of the toe and to hold the upper in close conformity to the contour of the last after the upper-tensioning operation.

22. In a machine of the class described, the combination with toe-lasting means, of means expandible by fluid pressure to press the forepart of an upper in conformity to the contour of the top and sides of a last, said pressing means being arranged to engage the sides of the upper only at the rear of its toe portion.

23. In a machine of the class described, the combination with toe-lasting means, of means expandible by fluid pressure to conform an upper to the contour of the top and sides of a last, said conforming means being arranged to engage the upper over the instep and terminating at a substantial distance from the toe end face of the last.

24. In a machine of the class described, the combination with toe-lasting means, of means expandible by fluid pressure to conform an upper to the contour of the top and sides of a last, said conforming means being limited to engagement with a portion of the upper at a substantial distance from both the toe and heel end faces of the last.

25. In a machine of the class described, a pad arranged to embrace an upper over the top and sides of a last and expandible by fluid pressure in conformity to the contour of the

last, said pad being mounted for movement widthwise of the last to adjust itself to the shape or position of the last.

26. In a machine of the class described, a pad arranged to embrace an upper over the top and sides of a last and expandible by fluid pressure in conformity to the contour of the last, said pad being mounted for movement widthwise of the last to adjust itself to the shape or position of the last, and yieldable means for normally centralizing the pad in respect to such movement.

27. In a machine of the class described, a fluid-pressure device arranged to embrace the top and sides of an upper on a last, said device comprising a pad expandible by fluid pressure in conformity to the contour of the last and a support for said pad mounted for rocking movement widthwise of the last to permit the pad to adjust itself to the shape or position of the last, and springs arranged to bear on the opposite sides of said support for normally centralizing it in respect to such movement.

28. In a machine of the class described, a pad arranged to embrace an upper over the top and sides of a last and expandible by fluid pressure in conformity to the contour of the last, said pad being adjustably movable about an axis extending widthwise of the last to position it in proper relation to lasts of different shapes or sizes.

29. In a machine of the class described, a pad arranged to embrace the top and sides of an upper over the instep portion of a last and terminating at a substantial distance from the toe end face of the last, said pad being expandible by fluid pressure in conformity to the contour of the last.

30. In a machine of the class described, a pad arranged to embrace the top and sides of an upper on a last and expandible by fluid pressure in conformity to the contour of the last, said pad being limited to engagement with a portion of the upper at a substantial distance from both the toe and heel end faces of the last.

31. In a machine of the class described, the combination with a toe rest for supporting the toe-end portion of a last with an upper thereon, of a pad arranged to engage the forepart of the upper at the rear of said toe rest and expandible by fluid pressure in conformity to the contour of the last.

32. In a machine of the class described, the combination with a toe rest for supporting the toe-end portion of a last with an upper thereon, of a pad arranged to embrace the instep portion of the upper and last at the rear of said toe rest and expandible by fluid pressure in conformity to the contour of the last.

33. In a machine of the class described, the combination with a toe rest for supporting the toe-end portion of a last with an upper

thereon, of a pad arranged to embrace the top and sides of the upper at the rear of said toe rest and expandible by fluid pressure in conformity to the contour of the last, said pad being movable widthwise of the last relatively to the toe rest to adjust itself to the shape or position of the last.

In testimony whereof I have signed my name to this specification.
